US00D555508S

(12) **United States Design Patent** (10) **Patent No.:** **US D555,508 S**
Py et al. (45) **Date of Patent:** ** *Nov. 20, 2007

(54) **DISPENSER OF A CONTAINER**

(75) Inventors: **Daniel Py**, Larchmont, NY (US);
Julian V. Chan, Spring Valley, NY (US); **Stephanie Ferreira**, Bridgeport, CT (US); **Luz Gladys Valencia**, Stamford, CT (US)

(73) Assignee: **Medical Instill Technologies, Inc.**,
New Milford, CT (US)

(*) Notice: This patent is subject to a terminal disclaimer.

(**) Term: **14 Years**

(21) Appl. No.: **29/237,874**

(22) Filed: **Sep. 7, 2005**

Related U.S. Application Data

(62) Division of application No. 29/198,292, filed on Jan. 27, 2004, now Pat. No. Des. 512,647.

(51) **LOC (8) Cl.** **09-03**

(57) **CLAIM**

The ornamental design for a dispenser of a container, as shown and described.

DESCRIPTION

FIG. 1 is a top and left side perspective view of a dispenser of a container showing our new design;

FIG. 2 is a top and right side perspective view thereof;

FIG. 3 is a left side elevational view thereof;

FIG. 4 is a back side elevational view thereof;

FIG. 5 is a right side elevational view thereof;

FIG. 6 is a top plan view thereof; and,

FIG. 7 is a bottom plan view thereof.

The broken lines in the figures show boundaries of the invention and form no part of the claimed design.
